ARLON LITTLEFIELD.

UNITED STATES PATENT OFFICE.

ARLON LITTLEFIELD, OF PROVIDENCE, RHODE ISLAND, ASSIGNOR TO NEW ENGLAND BUTT COMPANY, OF PROVIDENCE, RHODE ISLAND, A CORPORATION OF RHODE ISLAND.

CARRIER FOR BRAIDING-MACHINES.

1,124,480.

Specification of Letters Patent. Patented Jan. 12, 1915.

Application filed March 12, 1914. Serial No. 824,237.

To all whom it may concern:

Be it known that I, ARLON LITTLEFIELD, a citizen of the United States, and resident of the city of Providence, in the county of 5 Providence and State of Rhode Island, have invented certain new and useful Improvements in Carriers for Braiding-Machines, of which the following is a specification.

This invention relates to improvements in 10 carriers for braiding machines, and has for its object to provide a simple and effective feed control for the supply holder comprising a set of teeth in the holder releasably engaged by a pawl, and a yarn tension and 15 take-up arm adapted to act upon said pawl to raise it and permit the yarn to be released by the holder to supply the demand during the process of braiding.

A further object of the invention is to 20 provide a stop motion actuator and means in the tension arm for controlling the position of said actuator.

The invention further contemplates the 25 providing of means in said stop motion actuator whereby it may be caused to engage the stop motion and stop the machine whether the carrier be running either to the left or to the right.

With these and other objects in view, the 30 invention consists of certain novel features of construction, as will be more fully described and particularly pointed out in the appended claims.

Of the accompanying drawing: Figure 35 1— is a side elevation of the carrier showing the tension and take-up arm as raised and acting upon the pawl to raise it from its ratchet and release the supply holder. Fig. 2— shows the take-up arm in its extreme down position and as having moved 40 the stop motion actuator into operating position. Fig. 3— is a section on line 3—3 of Fig. 1 looking in the direction of the arrow and showing the stop lever in section having a portion extending on either side 45 of the frame whereby it may be caused to stop the machine when traveling either to the right or to the left. Fig. 4— is a front sectional view of the take-up arm pivot pin showing the arrangement of the spring for 50 actuating the same and the means for adjusting the tension of the spring. Fig. 5— shows the slotted head of the pivot pin. Fig. 6— is a top edge view of the take-up 55 arm.

Referring to the drawing, 10 designates the carrier frame which is provided with a standard 11 and a central fixed spindle 12 on which latter may be mounted the spool or holder for the supply of yarn. The supply may be of either the cop or bobbin type and the spool on which it is wound may have a ratchet head either at its upper or lower end, if desired. I have herein illustrated the common form of cop mounted on 60 a spur with its ratchet head 13 at its lower end, the same being provided with a plurality of teeth 14. I have also provided a pawl member 15 adapted to engage these ratchet teeth 14, said pawl being provided 65 with a body portion 16 adapted to slide vertically on the standard 11, and also on a pin 17 which passes through the body of the pawl and is supported at its upper end in the lug 18 and at its lower end in the lug 19 70 in the frame. I have also provided a small coil spring 20, one end engaging the underside of the lug 18 and the other resting upon the pawl whereby the latter is moved quickly back into engagement with the 75 ratchet teeth after having been raised to permit the holder to rotate for the purpose of releasing the yarn. In order to operate 80 this pawl by the action of the yarn I have provided an arm 21 which is fixed to the 85 pivot pin 22 by engaging a flattened portion 23 at its end, to which it is bound by the nut 24. This pivot pin is loosely mounted on the bushing 25 fixed in the frame 10, the head 29 of the pin being slotted as at 26, 90 see Figs. 4 and 5. A small disk 27 is mounted on this pivot and has a pin 28 adapted to engage the slots 26 in said pivot head 29 and a coil spring 30 is wound about the pivot with one end engaging the disk 27 and its 95 opposite end engaging the bushing 25 whereby a yielding tension is exerted on the arm which tension may be adjusted by pressing the disk 27 inward, rotating it against the coil and inserting the pin in another of the apertures 26. The end of this tension arm opposite its pivoting point is provided with a hook-shaped portion 31, and the yarn *a* is led down from the hole 32 in the standard on its way to the guide eye 100 33. This arm is provided with a laterally extending finger 34 which is adapted to engage the underside of the pawl body 16 to raise the pawl 15 out of engagement with its ratchet when this arm is drawn upward 105 110

by an excessive pull on the yarn during the process of braiding when more yarn is required to be released from the holder. This arm is also provided with a laterally extending finger 35 which is adapted to engage and control the operation of the stop lever presently described.

In devices of this character it is found necessary to provide means for engaging the usual stop motion of the machine to stop the latter when the yarn breaks or when an excessive amount of yarn has been released from the holder, and which is in danger of becoming entangled or knotted and liable to produce bad effects in the work. To accomplish this purpose in a simple and effective way I have provided a pair of lever members 36 and 37 located on opposite sides of the frame 10, see Fig. 3, both being pivoted by the single pin 38. Across the front of these levers is riveted a plate 39 which extends laterally a sufficient distance both to the right and to the left, so that this stop lever may be caused to engage the stop motion on the machine either when the carrier is traveling to the right or to the left. Where this provision is not made special carriers have to be constructed, some for a left hand travel and some for a right hand travel, but with my improved construction any of the carriers may be used for either the right or the left hand travel. In order to control the operation of this stop lever I have provided an upwardly extending portion 40 on one of the levers, the forward edge 41 of which is preferably made in a cam shape adapted to be engaged by the finger 35 of the tension yarn 31 by which it is normally held out of operating position. At the base of this cam curve is a shoulder 42 which is engaged by said finger 35 to force the stop lever into position to engage the usual stop motion and arrest the action of the machine when the tension arm is moved to its extreme down position under action of its spring 30.

I claim:

1. In a braiding machine, a carrier comprising a rotatable supply holder provided with ratchet teeth, a slidably mounted member carrying a pawl, means for depressing said member with its pawl in engagement with said teeth, a yarn tension and take-up arm, and means mounted on said arm for engaging said member to raise the same and disengage the pawl from said ratchet.

2. In a braiding machine, a carrier comprising a rotatable supply holder provided with ratchet teeth, a slidably mounted member carrying a pawl for releasably engaging said teeth, a spring pressed tension and yarn take-up arm, and a lug carried by said arm and adapted upon the raising of the latter a predetermined height to engage said member for raising the same to disen-

gage said pawl from said teeth to permit a portion of yarn to be withdrawn from the holder.

3. In a braiding machine, a carrier comprising a rotatable supply holder provided with ratchet teeth, a slidably mounted member carrying a pawl for releasably engaging said teeth, a spring pressed tension and yarn take-up arm, and a lug carried by said arm and adapted upon the raising of the latter a predetermined height to engage said member for raising the same to disengage said pawl from said teeth to permit a portion of yarn to be withdrawn from the holder, a stop motion actuating member, and means also carried by said tension arm adapted upon the dropping of the same a predetermined distance to engage and operate said stop motion control mechanism.

4. In a braiding machine, a carrier comprising a rotatable supply holder provided with ratchet teeth, a slidably mounted member carrying a pawl for releasably engaging said teeth, a spring pressed tension and yarn take-up arm, a lug carried by said arm and adapted upon the raising of the latter a predetermined height to engage said member for raising the same to disengage said pawl from said teeth to permit a portion of yarn to be withdrawn from the holder, a stop motion actuating member normally held out of operative position, and a lug carried by said tension arm adapted to engage said stop motion actuating mechanism when said arm drops beyond a predetermined position.

5. In a braiding machine, a carrier comprising a rotatable supply holder provided with ratchet teeth, a slidably mounted member carrying a pawl, means for depressing said member with its pawl in engagement with said teeth, a yarn tension and take-up arm, and means mounted on said arm for engaging said member to raise the same and disengage the pawl from said ratchet, a stop motion actuating mechanism comprising a pivoted lever, an abutment carried by one end of said lever and extending beyond both sides thereof, and a lug carried by said tension arm adapted to engage said lever for throwing said stop motion actuating mechanism in the operative position.

6. In a braiding machine, a carrier comprising a rotatable supply holder provided with ratchet teeth, a spring pressed member carrying a pawl for releasably engaging said teeth, a pivotally mounted spring pressed yarn tension arm, a lug carried by said arm for engaging and raising said spring pressed pawl carrying member to disengage said pawl from said teeth, a stop motion actuating member having a cam surface, and a lug carried by said arm for engaging said cam surface in the movement of said arm for placing said stop motion control mechanism in operative position.

7. In a braiding machine a carrier comprising a rotatable supply holder provided with ratchet teeth, a spring pressed slidably mounted member carrying a pawl for readily engaging said teeth, a pivotally mounted spring pressed yarn tension arm, a lug on said arm for engaging said member to raise said pawl and disengage said teeth, a pivotally mounted stop motion actuating lever having a cam surface, and a lug carried by said tension arm for engaging said cam whereby the movement of said arm controls the operation of said lever.

10 8. In a braiding machine, a carrier com-

prising a rotatable supply holder provided with ratchet teeth, a vertically slideable spring pressed member carrying a pawl normally in engagement with said teeth, a pivotally mounted spring pressed yarn tension 20 arm, and a lug carried by one end of said arm for engaging said member to raise the same whereby said pawl is disengaged from said teeth.

In testimony whereof I affix my signature 2
in presence of two witnesses.

ARLON LITTLEFIELD.
